WRITING INSTRUMENT

Nathan Alter Zepell, Fort Madison, Iowa, assignor to
W. A. Sheaffer Pen Company, Fort Madison, Iowa, a
corporation of Delaware

Filed Jan. 13, 1961, Ser. No. 82,535
7 Claims. (Cl. 120—43)

This invention relates to writing instruments and has special reference to a fountain pen of the type having a retractable writing element and control means adapted to exclude air from the fluid reservoir and supply channels.

More particularly, this invention pertains to a fountain pen comprising a barrel having an open forward end, a fluid reservoir within the barrel, a writing element housed within the barrel forwardly of the reservoir section and terminating in a valved tip having a flexible writing point, an actuating unit carried by the barrel and including a manually operable portion extending outside of the barrel and engaging the internally disposed reservoir to reciprocate the writing element and thereby move the writing point through the open forward end between the exposed position and concealed position, there being a feed member communicating between the reservoir and the tip whereby when the writing point is flexed fluid is directed thereto for writing.

In the usual type of fountain pen, it is necessary to provide for entry of air into the reservoir to replace the fluid used during writing. Due to the difference in weight, the air rises above the writing fluid and remains thereabove regardless of the position in which the fountain pen subsequently may be held.

The air thus present in a fountain pen reservoir will expand or contract if the implement is subjected to fluctuations in temperature and/or pressure.

An increase in temperature or a decrease in barometric pressure may readily cause an undesirable condition in the usual fountain pen should it be held in a position resulting in isolation of air in the closed end of the reservoir, as while writing. Under these conditions a quantity of fluid, equal to the increase in air volume, will be forced from the reservoir and into the expansion chambers of the feed. Should the expansion chambers not be of sufficient capacity, a portion of this fluid will drip from the writing instrument into the cap or blot the writing surface or soil the user's hands or clothing. It has been observed that this is a particularly acute problem in air travel, in which great extremes of temperature and pressure may be encountered in relatively short periods of time.

Further, in the usual type of fountain pen, it is necessary to provide a cap or other means for isolating the point and feed assembly from the atmosphere to prevent evaporation of the volatile constituents of the writing fluid. As is well recognized in the art, such evaporation is particularly undesirable because of the resultant "drying out" and subsequent hard starting of the pen. However, the usual fountain pen cap may readily become separated from the balance of the instrument, resulting in loss or damage, whereafter it is practically impossible for the user to carry the implement without soiling his clothing.

Furthermore, in present day fountain pens the overall capacity of the reservoir is limited as a result of the above described problem of expansion of air which may be trapped above the fluid. This necessitates relatively frequent refilling of the pen. And while the prior art includes a number of suggestions for means of controlling a large capacity, such as reservoir valves, capillary inserts and the like, none of these arrangements have proven commercially successful. Thus, the advantages of a

2

large capacity have long been recognized, but it has not been practical to provide such a capacity prior to this invention.

Accordingly, it is a principal object of this invention to provide a fountain pen having a reciprocal writing element which does not require isolation from the atmosphere when in the storage or concealed position.

Another object of this invention is to provide a fountain pen which has a large fluid capacity but which is not subject to leaking or flooding as a result of temperature or barometric pressure changes.

A further object of this invention is the provision of a fountain pen in which the writing fluid is contained in a vented reservoir section having means therein between the fluid and the atmosphere and movable in response to withdrawal of fluid during writing.

A still further object of this invention is to provide a fountain pen having a writing unit assembly which seals the fluid supply channel to prevent evaporation while the implement is not in writing use.

Yet another object of this invention is the provision of a fountain pen having a writing unit assembly which is adapted for use with a replaceable fluid cartridge and which is reciprocal as a unit with such a cartridge in order to move the writing tip between concealed and writing positions while the fluid supply is sealed from the atmosphere.

Further and additional objects of this invention will be apparent from the following description when taken with the accompanying drawings, in which:

FIG. 1 is a broken longitudinal sectional view of a fountain pen embodying this invention and illustrating the arrangement of parts as conditioned for storage;

FIG. 2 is an enlarged fragmentary sectional view of the forward portion of the embodiment of FIG. 1 showing a change in position of the parts as conditioned for writing;

FIG. 3 is an enlarged fragmentary sectional view of the forward portion of the embodiment of FIG. 1 showing the position of the parts during writing; and

FIG. 4 is an exploded view of the writing and support elements of the writing unit assembly as incorporated in the embodiment of FIG. 1.

Referring now to FIG. 1 of the drawing, the fountain pen illustrated therein includes a barrel 10 which, for convenience in manufacture and assembly, comprises a forward portion 12 and a rearward portion 14 threadedly secured in axial alignment. While various materials may be used for these barrel portions, in the illustrated embodiment the forward portion 12 preferably is molded of a plastic material having good dimensional stability and a lustrous and long wearing surface, with the outer shell or cap of the rearward portion 14 being formed of a metal such as stainless steel or the like. The forward and rearward barrel portions are held in axial alignment by the threaded coupling 16 which is frictionally retained adjacent the open end of the rearward barrel portion 14.

Disposed within the barrel 10 is a fluid reservoir section 18 which may be provided in the form of a disposable cartridge as shown in the illustrated embodiment. The cartridge consists of an elongated generally cylindrical body portion 20 made of any one of a number of materials which are substantially inert to the constituents of the usual writing fluid. However, because of its "toughness" and resistance to breakage, a relatively resilient plastic such as polypropylene or polyethylene is preferred. At the forward end of the body portion 20 is a closure disc 22 which may be formed as a separate piece, as illustrated, or molded integral with the body portion 20. As will be described in more detail hereinafter, the closure disc 22 includes a centrally disposed bore 24 ex-

tending through an upwardly projecting collar or stop means 25.

One of the features of this invention is the prevention of any possibility of a build-up of pressure within the reservoir regardless of temperature or pressure conditions. As will be explained in more detail herebelow, this feature is accomplished by reducing the "effective" volume of the reservoir as fluid is drawn therefrom during writing, thereby eliminating any necessity of intermixing air and fluid in the reservoir. As will be understood, the term "effective," as used herein, refers to the volume actually displaced by fluid in the reservoir.

The rearward end of the body portion 29 is furnished with a washer 28, having a centrally disposed aperture or vent 30 which is in communication with the atmosphere through the interior of the barrel 10. As will be readily apparent from the following description, the vent 30 is for the purpose of allowing reduction of the "effective" volume of the reservoir as fluid is used in writing.

Housed within the barrel 10 forwardly of the reservoir section 18 is a writing unit assembly 32 which is longitudinally reciprocable within the bore 36 and the eccentric bore 34 which extends through the forward end of the barrel portion 12. The writing unit assembly 32 includes a writing element 38 made of a gold or other non-corrodible alloy and terminating at its forward end in a valved tip 40, which includes a pair of nib portions defining a flexible or displaceable writing point 41. As can best be seen in FIG. 4, the tip 40 includes longitudinally aligned apertures 42 and 44. Extending between the apertures 42 and 44 is a minute opening 46, and extending forwardly of the lower aperture 44 and between the nibs is a slit 48 normally which is closed except upon contact of the writing point 41 with a writing surface. To a substantial degree, the flexibility of the writing tip 40 may be controlled by the thickness of the material from which the writing element 38 is fabricated, in combination with the generally arcuate shaped side cutouts 50 which are provided immediately above the writing tip.

In order to conduct writing fluid from the reservoir 18 to the valved tip 40, there is mounted within the writing element 38 a feed member 52 which generally may be cylindrical in configuration. The forward end of the feed member 52 preferably is reduced in diameter and provided with a transversely disposed end 54 which terminates in an outlet 56 extending into the lower aperture 44 of the valved tip 40, as can best be seen in FIGS. 2 and 3.

As previously mentioned, the fluid reservoir 18 may be provided in the form of a disposable cartridge, and for this reason, the upper end of the feed member 52 extends rearwardly beyond the writing element 38 for detachable engagement with the bore 24 of the closure disc 22. The upper end of the feed member 52 preferably is cut on a bias so as to provide a sharp cutting edge or point 58, adapted to pierce readily the usual diaphragm or membrane as may be provided on the closure disc 22 in order to seal the bore 24. Although various other arrangements may be used in order to hold the writing element and feed member assembled, it is preferred to spin or otherwise form the rearward end of the writing element 38 inwardly to form an annular ring 60 in an adjacent recess in the outer surface of the feed member.

One of the features of the present invention is the elimination of the necessity of using a separable cap or any other mechanism for protecting the writing point or sealing the writing unit assembly from the atmosphere. This is accomplished by the valved tip 40, which includes means adapted to close the outlet 56 except when the writing point 41 is displaced or flexed during use. Referring particularly to FIGS. 2 and 3, there is shown a cover 62 which overlies at least a portion of the valved tip 40; preferably, it substantially envelops the tip. While this cover member 62 may be preformed as by molding, it is preferred to apply it to the writing element 75

by a dipping or spraying process. So as not to interfere with the displacement or flexing of the writing tip during use, the cover 62 should be relatively thin and resilient, such resiliency being provided by several well-known rubber or plastic compounds. One such compound may include latex particles dispersed in an aqueous vehicle.

As best illustrated in FIGS. 1 and 2, the outlet 56 normally lies on a plane substantially level with the upper surface of the valve tip 40. Thus, when the tip 40 is in the normal unflexed condition, the cover means 62 will effectively seal the outlet 56 to prevent any egress of ink therefrom. Accordingly, there is communication between the outlet 56 and the forwardly extending slit 48 only during such time as the writing point 41 is flexed upwardly during writing as shown in FIG. 3.

Prior to applying the cover means 62 to the writing element 38, a plug or the like is inserted into the forward aperture 44 so that the aperture is not filled with the material of the cover 62 during the dipping or spraying process. The subsequent removal of the plug results in a slight flange of material around the underside of the aperture 44, which flange slidably but sealably engages the outer circumference of the transverse end 54 of the feed member 52. This feature is illustrated best in FIG. 3, which clearly shows that while the pen is in use, writing fluid will be confined within the forward aperture 44 and the forward slit 48 which is surrounded by the cover means 62. Thus, the only contact between air and ink will be at the extreme forward end or writing point 41 of the valved tip 40 during actual writing use of the pen.

Another feature of the cover means 62 is that it will positively prevent any transfer of fluid from the writing element 38 to the inner surface of the barrel 12 as defined by the bore 34.

The top portion of the bore 34 preferably is flared outwardly from the axis of the pen to provide sufficient room for limited flexing of the valve tip 40. Or alternately, the bore 34 may be made slightly oversize with respect to the size of the writing element 38. Regardless of the particular arrangement utilized, however, the top portion of the bore 34 forms a stop against which the tip 40 may abut during writing thereby preventing too great a flow of fluid from the outlet 56. Merely as an example, the valved tip 40 preferably is allowed to flex between 5-15 thousands of an inch when using an outlet on the order of 10-15 thousandths inside diameter. A larger or smaller outlet, of course, may require a smaller or greater amount of movement of the tip 40 in order to secure a proper flow of fluid.

Overlying the cover means 62 is a support member 50 which is formed of a semi-rigid plastic or metal. As illustrated best in FIG. 4, the support member utilized in the embodiment is in the form of a sleeve 66, the top portion of which is provided with a plurality of slits 68 extending to the forward end of the sleeve 66. The resultant "tongue" portion 70 will flex readily upon movement or displacement of the valved tip 40. The rearward end of the sleeve 66 is provided with an annular head 72. The sleeve 66 is sized so as to frictionally receive the writing element 38, with the rearward end of the writing element 60 abutting the inwardly extending portion of the annular head 72. The feed member 52, as discussed previously, extends rearwardly beyond the head 72 of the sleeve 66 for detachable engagement with the cartridge reservoir section 18.

Carried by the upper barrel portion 14 is an actuating unit which is engaged with and adapted to move the reservoir section 18 and writing unit assembly 32 forwardly so as to extend the writing point 41 of the tip 40 beyond the forward barrel portion 12. This actuating unit includes a manually operable portion 74 which extends outside of the barrel and which also serves as a pocket clip in the present embodiment. An internally mounted actuating spring 76 is operatively engaged with an inwardly directed portion 75 which is provided on the dependent

end of the clip portion 74, such engagement being permitted by an aperture 75 disposed in the upper barrel portion 14 adjacent the inwardly directed portion 75. As described in more detail hereinbelow, the actuating spring 76 is arranged for engagement with a driving member 78 which is disposed within the barrel 10 in abutment with the fluid reservoir 18. The clip member 74 and the actuating spring 76 are secured together at the mounting portion 80, and are pivotally movable as a unit about the point 81 on the upper barrel portion 14. Thus, as will be apparent, manual movement of the forward or dependent end of the clip portion 74 inwardly toward the axis of the pen will result in movement of the inwardly directed portion 75 through the aperture 77 and conjoint movement of the actuating spring 76, thereby forcing the driving member 78 forwardly as a result of engagement of the enlarged lower end 82 of the spring member 76 with the inclined surface 84 of the driving member 78. Retraction of the reservoir section 18 and writing unit assembly 32 is then effected by manual pivotal movement of the clip member 74 and spring 76 in an outward direction.

Disposed between the outwardly extending portion of the head 72 and shoulder 86, formed by the concentric bores 34 and 36, is a resilient coil spring 88. The purpose of the spring 88 is to urge the writing unit assembly 32 and reservoir section 18 rearwardly to the tip concealed position illustrated in FIG. 1 upon outward pivotal movement of the clip member 74 and actuating spring 76.

During replacement of the cartridge reservoir section 18, there will be a rearward pull on the writing unit assembly 32 as a result of frictional contact between the rearward end of the feed member 52 and the bore 24. Also, the coil spring 88 will exert a rearwardly directed force on the head 72 of the sleeve 66. Because of the possibility of abuse to the writing unit assembly 32 should it be withdrawn from the pen during removal or replacement of the cartridge reservoir, the sleeve 66 is provided with a radially extending finger 90 slidably within a groove 92 formed as an outward extension of the bore 34. A collar 94 is then threadedly engaged with the rearward end of the bore 34 to act as a means of limiting rearward movement of the finger 90. Furthermore, because of the finger 90 and groove 92, the writing unit assembly 32 is positively prevented from any undesirable axial rotation.

As outlined hereinbefore, the aperture 30 acts as a vent to provide communication between the atmosphere and the interior of the reservoir section so as to eliminate any possibility of an increase in pressure on the writing fluid and subsequent expulsion of such fluid from the reservoir. To prevent escape of writing fluid through the vent 30 should the pen be inverted, and evaporation of the volatile elements of the writing fluid, means is provided within the reservoir and between the vent 30 and the writing fluid. While the means may take several forms, it is shown in the instant embodiment to comprise a follower 96 which sealably but slidably engages the interior wall of the body portion 20 of the reservoir section 18. To insure against sticking of the follower 96 within the reservoir as it descends with the level of the writing fluid, it preferably should be of a deformable nature. Such a characteristic may be provided by forming the follower 96 of a flaccid plastic or rubber, a viscous grease or a gelatinous material.

As the writing fluid in the reservoir section 18 nears depletion the follower 96 will engage the upwardly extending collar 26 provided on the closure disc 22. Collar 26 thus insures that none of the material of the follower 96 will come into contact with or enter the feed path within the feed member 52. As can readily be understood, the feed member 52 must be maintained free of any foreign material which might interfere with the proper flow of fluid during use of the fountain pen.

When the forward surface of the follower 96 reaches the rearward edge of the collar 26, it may trap a small

quantity of writing fluid in the annular space between the outer surface of the collar 26 and the inner surface of the body portion 20. And in order to use at least a part of this trapped fluid, there is provided one or more capillary fissures 98 communicating between the annular space and the bore 24.

To condition the herein described embodiment for writing, the only action required on the user's part is a mere inward movement of the lower end of the clip member 74 through aperture 77. Such inward movement results in corresponding inward movement of the lower end 82 of the actuating spring 76, and subsequent forward movement of the driving member 78. As the driving member 78 moves in a forwardly direction, the reservoir section 18 and writing unit assembly 32 are urged forwardly against the action of the coil spring 88 until the writing point 41 is positioned slightly beyond the lower barrel portion 12. In this position, the writing point 41 may then be pressed against paper or a similar writing surface and displaced upwardly relative to the outlet 56 of the feed member 52. Capillary attraction between the writing point 41 and the writing surface will then draw fluid from the reservoir section 18 through the feed member 52 and slit 48.

The above described withdrawal of fluid will cause forward movement of the follower 96 within the reservoir 18 thus reducing the "effective" volume thereof, until the fluid is completely exhausted. Such forward movement of the follower 96, of course, requires the entry of air into the reservoir rearwardly of the follower through the above described air pathway consisting of the interior of the barrel 10, and the vent passage 30, which are connected by the channel 100 provided on the forward end of the driving member 78.

The fit between the writing unit assembly 32 and the bore 34 is relatively loose and the space thus provided will allow movement of air between the interior of the barrel and the atmosphere. However, upon extension and retraction of the fluid reservoir 18, the movement of air will be quite rapid and to facilitate this air movement, there is provided an aperture 104 extending from the bore 36 radially through the barrel portion 12.

As mentioned hereinabove, writing fluid within the reservoir section 18 is completely protected against any contact with air except at the writing point 41 during use of the pen. Thus, when outlet 56 is closed during non-writing, and regardless of whether or not the writing element 37 is in the retracted or extended position, there will be no evaporation of fluid from the reservoir or feed channels, and only the slight amount remaining at the point 41 will be subject to contact with air. However, the very minute amount of dried coloring material which may be left at the point 41 will be sufficient to interfere with subsequent flow of ink, particularly since such dried material will be redissolved and washed away quickly.

Although the follower 96 will move forwardly within the reservoir as fluid is withdrawn during writing, it will be understood by those in the art that no rearward movement of the follower 96 will occur should the implement be inverted. This feature is provided by the slight amount of friction or adhesion which is present between the follower 96 and the interior wall of the body portion 20, and further by the effective sealing of the outlet 56 whereby no air is permitted to enter the feed member 52 or reservoir 18.

Upon depletion of the fluid supply in the reservoir section 18 the upper barrel portion 14 may be disengaged from the lower barrel portion 12, and the empty reservoir section removed and replaced by a fresh cartridge. During such time as the barrel portions may be disassembled, the driving member 78 will be retained within the upper barrel portion 14 by means of the shoulder 102 formed by the upper edge of the coupling 16.

It is understood that although only one embodiment is illustrated and described herein, the invention is not to be

limited thereto as many modifications may be made without departing from the true spirit and scope of this invention. Accordingly, this invention is not to be limited to the embodiment described above and it is contemplated, by the appended claims, to cover any such modifications which fall within its true spirit and scope.

I claim:

1. A writing instrument comprising a barrel having an open forward end, a reservoir section within said barrel, said reservoir section comprising a fluid cartridge having a vent passage for communication with the atmosphere, a writing element extending forwardly of said reservoir section, said writing element being provided on its forward end with a longitudinal slit to define resilient nibs forming a flexible writing point, and an aperture in communication with said slit, a feed member adapted for communication with said cartridge and providing an outlet disposed in said aperture intermediate the ends of said slit, a thin layer of resilient material bonded to and substantially enveloping said writing point for sealingly engaging said outlet and being disengaged therefrom when said nibs are flexed during writing, and means in said cartridge for restraining said fluid against movement through said vent, said means being movable to reduce the volume of said cartridge in response to withdrawal of fluid through said writing point.

2. A writing instrument comprising a barrel having an open forward end, a reservoir section within said barrel, said reservoir section comprising a fluid cartridge removably received within said barrel and including a vent passage for communication with the atmosphere, a writing element extending forwardly of said reservoir section, said writing element being provided on its forward end with a longitudinal slit to define a pair of resilient nibs forming a flexible writing point and an aperture in communication with said slit, a feed member detachably connected to said cartridge and providing an outlet disposed within said aperture, a thin layer of resilient material substantially enveloping said nibs for sealingly engaging said outlet and being disengaged therefrom when said nibs are displaced, said resilient means sealingly engaging said nibs along said slit to confine said fluid to said slit as it is withdrawn during writing, and means in said cartridge for restraining said fluid against movement through said vent passage, said means being movable to reduce the volume of said cartridge in response to withdrawal of fluid through said slit.

3. A writing instrument comprising a barrel having an open forward end, a fluid cartridge removably received within said barrel, said cartridge including a vent passage for communication with the atmosphere, a writing element extending forwardly of said cartridge, said writing element being provided on its forward end with a longitudinal slit to define a pair of resilient nibs forming a flexible writing point and an aperture in communication with said slit, a feed member detachably engaging said cartridge and providing an outlet disposed intermediate the ends of said slit, a thin layer of resilient material substantially enveloping said nibs for sealingly engaging said outlet in the absence of flexure in said nibs, said means being disengaged from said outlet to permit movement of fluid therethrough only when said nibs are flexed, said resilient means sealingly engaging said nibs along said slit to confine said fluid to said slit as it is withdrawn during writing, a resilient support member overlying said resilient means, and means in said cartridge for restraining said fluid against movement through said vent, said means being movable to reduce the volume of said cartridge in response to withdrawal of fluid through said slit.

4. A writing unit assembly for a fountain pen of the type having a barrel and a fluid reservoir section adapted to contain a supply of writing fluid within said barrel, comprising a generally cylindrical writing element extending forwardly of said reservoir section and terminating in

8

a pair of resilient nibs defining a fluid path therebetween, said writing element including an aperture communicating with the rearward end of said fluid path, a generally cylindrical feed member communicating with said reservoir section, said feed member being mounted within said writing element and having a transverse portion providing an outlet disposed within said aperture, and resilient means substantially enveloping said nibs and normally engaging said transverse portion for sealing said outlet and being disengaged from said portion to permit fluid movement through said outlet when said nibs are displaced.

5. A writing instrument comprising a barrel having an open forward end, a fluid reservoir within said barrel, a writing element extending forwardly of said reservoir section and terminating in a flexible writing tip and an aperture in communication with said slit, a stop provided by said barrel for limiting the flexure of said writing tip, a feed member communicating with said reservoir section and providing an outlet disposed adjacent said tip, and means consisting of a thin layer of resilient material bonded to and substantially enveloping said writing element providing a barrier against fluid transfer between said writing tip and said stop.

6. A writing unit assembly for a fountain pen of the type having a barrel and a fluid reservoir section adapted to contain a supply of writing fluid within said barrel, comprising a writing element extending forwardly of said reservoir section and terminating in a pair of resilient nibs defining a fluid path therebetween, said writing element including an aperture communicating with the rearward end of said fluid path, a feed member communicating with said reservoir section, said feed member being mounted within said writing element and having a transverse portion providing an outlet disposed within said aperture, and resilient means substantially enveloping said nibs and normally engaging said transverse portion for sealing said outlet and being disengaged from said portion to permit fluid movement through said outlet when said nibs are displaced.

7. A writing unit assembly for a fountain pen having a fluid reservoir, said assembly comprising a writing element extending forwardly of said reservoir and terminating in a pair of displaceable nibs defining a fluid path therebetween, said writing element having an aperture communicating with said fluid path, a feed member communicating with said reservoir and having a portion extending from one side of said writing element and providing an outlet disposed within said aperture, and resilient means affixed to the opposite side of said writing element and at least partially covering the aperture, said resilient means being positioned to engage and seal said outlet and being disengageable from said outlet to permit the flow of fluid therethrough and into said aperture and fluid path only when said nibs are displaced.
